C. HAYES

PROCESS OF CARBONIZATION OF COAL

Filed Dec. 10, 1925

UNITED STATES PATENT OFFICE.

CHARLES HAYES, OF PARIS, FRANCE, ASSIGNOR TO COAL CARBONIZATION COMPANY,
A CORPORATION OF DELAWARE.

PROCESS OF CARBONIZATION OF COAL.

Application filed December 10, 1925. Serial No. 74,542.

My invention relates to low temperature carbonization of coal and has for its object to provide a process by which carbonization of coal at low temperature may be rapidly and economically effected, and particularly to provide a process of agitation of the coal under treatment by which an even heating of the charge is brought about and sticking of any portion of the charge to the walls of the retort or digester is prevented. A further object of the invention is to provide a process by which the charge may be solidified by compression.

With the objects above pointed out my invention consists in the process hereinafter described and claimed.

Referring to the drawings Figure 1 is a vertical longitudinal central sectional view of an apparatus adapted to carry out the process of my invention.

Figure 2 is a cross sectional view on line 2—2 of Figure 1.

Figure 3 is a detail view of means for oscillating and rotating the retort or digester.

Figure 4 is a diagrammatic view illustrating the oscillating and rotating movement of the retort or digester.

In the drawings 1 indicates the retort consisting of a cylindrical tube of considerable length relative to its diameter arranged to rotate on a horizontal axis and having one end provided with a fixed head 2 having a central opening in which is secured the end of a tube 3 open at both ends and adapted to rotate in a suitable bearing on support 4. The outer end of tube 3 extends into and rotates freely in an opening in a manifold 5. Fast on the tube 3 is a sprocket gear 6 which by means of sprocket chain 7 is operatively connected with the driven gear 8 which by means of a driving gear 9 of spiral construction and which forms the subject matter of a separate application for Letters Patent of the United States filed by me December 10, 1923, Serial No. 74,540 and which is adapted to impart to the retort 1 rotation through a predetermined arc, for instance one-fourth of a rotation in one direction, then to stop its rotation and impart rotation in the opposite direction through a predetermined arc of greater extent, and then to stop its rotation and again reverse, the effect being that the charge within the retort is rotated first in one direction and then in the

other, the retort being gradually caused to rotate through a complete rotation. Other means for imparting to the retort the oscillatory rotating movement described may be used such as that described in the patent to Doran, No. 1,215,503, Feb. 13, 1917.

The retort is supported at one end by the tube 3 in its bearing on the support 4 and at the other end is supported by rollers 11 on opposite sides of its axis.

Within the retort 1 is a movable head 12 in the form of a trunk piston having the forward end of its skirt preferably tapered outward so as to be adapted to scrape the interior of the retort. The digester is open at the end opposite the fixed head 2 and is enclosed by a hood 13 which extends upward from a receiving bin 14 arranged below the level of the retort. Below the digester is arranged the fire box or combustion chamber 15. Any convenient heating means may be employed the heating means here shown consisting of a series of gas burners carried by a gas supply pipe 16. The combustion chamber communicates at its forward end with 75 the hood 13.

At the forward end of the retort the hood 13 is provided with vertically sliding door 17 movable in ways 18 for closing the end of the retort, this door being preferably provided with openings 19. Opposite the end of the retort and in line with it the hood 13 is provided with a second sliding door 20.

Two or any number of retorts may be arranged in battery with a single traveling 90 means for filling the digesters and a single traveling means for expelling the contents of the retorts after treatment. In the construction shown the filling means comprises a scoop 21 of substantially the same length as 95 the retort and a ram 22 preferably hydraulic, air or steam operated, by which the scoop, previously filled with coal may be pushed into the retort for its entire length pushing back with it the trunk piston 12 100 if the latter is not against the fixed head 2. When the scoop has been pushed within the retort its contents may be held against rearward movement by any convenient means and the scoop withdrawn, leaving its contents in the retort.

The ram 22, and preferably also the scoop 21, may be mounted to be movable on rails 23 to bring it in line with any one of the retorts of the battery.

The sliding doors 17 and 20 being closed the heat from the burners in the combustion chambers heat the retort exteriorly heating the charge by conduction and radiation. Assuming the charge to be bituminous coal high in volatiles, the heat used is sufficient to bring the charge to a temperature of from 700 degrees F. to not over 1000 degrees. The volatiles pass between the periphery of the movable head 12, and the wall of the retort this movable head, in order to be capable of being moved in the retort, necessarily fitting loosely enough to permit gases and vapors to pass, and the volatiles then pass off through tube 3 in the fixed head 2 and through manifold 5 from which they are drawn by an exhaust fan 24, the volatiles so drawn off, consisting of condensable vapors and fixed gas being led to a condenser (not shown) the condensed oils being separated out and the uncondensable gas being made use of for heating the retort or for other purposes.

The products of combustion from the combustion chamber 15 passing into the hood 13 are preferably drawn into and through the charge in the retort by the current created by the exhaust fan 24 aiding in the heating of the charge and also aiding in carrying off the volatiles, these products of combustion being, of course, inert, that is free from oxygen capable of sustaining combustion within the retort.

When the charge has been sufficiently treated and is in the pasty or sticky condition which results from being heated for a substantial period at the relatively low temperature above indicated, a ram 25, hydraulic or air or steam operated, and mounted to be movable on tracks 26, is moved into line with the retort containing the treated charge and, the plug closing the opening 27 in the manifold 5 being removed, the rod 28 is pushed through this opening 27 and through tube 3 against movable head 12 and the sliding door 17 being in closed position, further forward movement of this rod 28 effects a compression of the charge between the closed door 17 and the movable head. When this compression has been carried to the desired extent the sliding door 17 is raised and, the movement of rod 28 being continued, the compressed charge is forced out into the hood 13 and drops into the bin 14 where it is retained out of contact with the air until it has so far cooled that it will not ignite on contact with the air. The door 29 permits removal of the contents of the bin.

After the compressed charge has thus been forced out of the retort the pusher rod 28 is withdrawn. This leaves the movable head at or near the discharge end of the retort. The door 20 of hood 13 may

then be opened and the scoop 21 having been reloaded is again pushed into the retort to leave its load as before.

During the heating of the charge the retort is subjected to the oscillating rotary movement above described and by reason of the agitation thus given to the charge its even heating throughout its mass is ensured and at the same time overheating of the portion next to the wall of the retort, at least to the point of being so carbonized as to adhere to the wall is prevented. With a non-rotary retort or a retort rotated continuously in one direction only there is a tendency of the softened coal or tarry matter resulting from the heat action to stick to the wall of the retort and, as the heat continues and becomes more intense the matter sticking to the retort wall is burned to a condition similar to hard carbon and is discharged with difficulty. By reversing the rotation of the retort the momentum of the charge causes a slipping between the material in contact with the wall and the wall itself and it is probable that the unsoftened material of the charge is mixed with the softened portion in such a way that the tendency to stick to the walls is overcome. By reason of the fact that the oscillation in one direction is through an arc of greater extent than the oscillation in the other direction the retort is eventually given a complete rotation so that the heat from the combustion chamber though applied only to the lower portion of the retort does not heat it so unequally as to produce distortion.

While the process of my invention has been described as intended for use in carbonization of coal it will of course be understood that the term coal is intended to include any and all carbonaceous material capable of heat treatment to drive off volatiles.

It is of course to be understood that the term "coal" as used herein includes all carbonaceous material from which volatiles may be driven by heat and while my process is particularly adapted and intended for use in coal carbonization it is not to be understood as limited to use with any particular material but includes its use in connection with heat treatment in a retort, digester or kiln, of any material which is liable to adhere to the walls.

I do not herein claim the apparatus for carrying out the process herein claimed as that forms the subject matter of my application for Letters Patent of the United States filed December 10, 1925, Serial No. 74,541, nor do I claim the special gearing for effecting the oscillation and rotation as that forms the subject matter of my application filed December 10, 1925, Serial No. 74,540.

Having thus described my invention what I claim is:

1. In carbonizing coal and like carbonaceous materials carrying volatiles within a rotary retort, subjecting the material within the retort to heat applied to the exterior of the retort, and agitating the material and preventing it from adhering to and building up on the wall of the retort, 35
- 10 by repeatedly rotating the retort first in one direction through a predetermined arc and then in the other direction through a greater arc so that by successive movements 40 complete rotation of the retort will be effected.
- 15 2. In carbonizing coal and like carbonaceous materials carrying volatiles within a retort, subjecting the material within the retort to heat directed against the exterior 45 of the retort along a portion of its circumference only, and agitating the material and preventing it from adhering to and building up on the wall of the retort, by repeatedly rotating the retort first in one direction through a predetermined arc and then in the other direction through a greater arc so that by successive movements the entire circumference of the retort will be subjected to the direct action of the heat. 50
- 20 3. In carbonizing coal and like carbonaceous materials carrying volatiles within a 55
- 25
- 30

rotary retort, subjecting the material within the retort to heat applied to the exterior of the retort to drive off volatiles, and agitating the material and preventing it from adhering to and building up on the wall of the retort, by repeatedly rotating the retort first in one direction through a predetermined arc and then in the other direction through a greater arc so that by successive movements complete rotation of the retort will be effected, and drawing off the volatiles set free by the heat and continuing the agitation during their withdrawal.

4. In carbonizing coal and like carbonaceous materials carrying volatiles within a rotary retort, subjecting the material in the retort to heat applied to the exterior of the retort and agitating the material and preventing it from adhering to and building up on the wall of the retort by repeatedly rotating the retort first in one direction through a predetermined arc and then in the other direction through a greater arc so that by successive movements complete rotation of the retort will be effected, drawing off volatiles set free by the heat and compressing the material within the retort.

In testimony whereof, I hereunto affix my signature.

CHARLES HAYES
